J. L. MARTIN

STENCIL HOLDER

Filed Sept. 2, 1924

FIG. 1

INVENTOR
JESSE L. MARTIN

BY
Joseph B. Gardner
ATTORNEY

Patented Aug. 17, 1926.

UNITED STATES PATENT OFFICE.

JESSE L. MARTIN, OF OAKLAND, CALIFORNIA.

STENCIL HOLDER.

Application filed September 2, 1924. Serial No. 735,309.

My invention relates to a device for holding stencils while in use.

An object of the invention is to provide a stencil holder which will firmly grip the stencil without mutilating it and at the same time permit the ready removal or replacement of the stencil.

Another object of the invention is to provide a stencil holder by means of which the stencil may be applied to and held against a surface without necessitating the touching of the stencil by the hands of the operator.

A further object of the invention is to provide a stencil holder by which a stencil may be held fixedly extended while in use.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a back view of the stencil holder of my invention showing a stencil held therein.

Figure 2 is a sectional view taken on the line 2--2 in Figure 1.

In using a stencil for the marking of containers and other objects, considerable difficulty has been encountered both in handling the stencil when applying it and in holding it flat against the surface to be stenciled. These difficulties have been usually overcome by securing the stencil to a holder, but the use of holders heretofore provided has involved the permanent fastening of the stencil thereto and its consequent mutilation by nail holes and the like. In accordance with my invention, however, I provide a stencil holder which, while providing the desired aid in handling the stencil, also provides for the ready removal or replacement of the stencil.

In the present embodiment, the stencil holder of my invention comprises a body member 4 having oppositely disposed flat sides 5. Extending transversely through the body adjacent an end 7 thereof is a perforation 6 through which a flat metallic band 8 is arranged to pass. The band 8 preferably

extends from the perforation 6 along both of the sides 5 to the opposite end 9 of the body member where its ends are secured by means of a nail or screw 11.

It will now be noted that the space between the band and either side 5 is adapted to receive a flat stencil plate 12 of the usual type. Means are provided for gripping the plate 12 in the before-mentioned space and as here shown comprise a bolt 13 which is arranged to stretch the band longitudinally and thereby cause the forcible engagement of the plate 12 between the face 5 and the band. In the present embodiment, the bolt 13 extends through a longitudinal member 18 extends through a longitudinal perforation 14 in the body end 7 and a perforation 15 in the band to engage in a nut 16 which is held against rotation inside and against the band. In this manner, it will be noted, rotation of the member 13 in one direction will cause it to bear against the side 17 of the perforation 6 to cause a longitudinal stretching and consequent tightening of the band against the surfaces 5, whereas a rotation of the member 13 in the other direction will loosen the band to allow the removal or insertion of a stencil. The bolt 13 is preferably formed with a hook-like curved portion 18 at its outer end, the portion 18 being used to assist in turning the bolt or as a means for hanging the holder on a hook as may be required.

By providing a curved notch 19 for the reception of the band at the end 9 of the holder body and correspondingly notching the body portion adjacent the perforation 6, the band is caused to assume the shape of an elongated ellipse. In this manner the best possible contact between the band and surfaces 5 is assured when the band is stretched as described since the elongation of the ellipse causes a corresponding tendency to draw the opposite sides toward each other to forcibly engage the sides 5 of the holder body.

With a stencil held in the holder of my invention, it will now be obvious that it may be readily handled and that the stencil is held flat. Furthermore, release of the stencil is effected upon a comparatively slight rotation of the bolt 13, thereby providing for the rapid changing of stencils. Since gripping of the stencil is accomplished entirely by engagement between the band and holder body side it will also be noted that any flat stencil may be held

in the holder without involving its mutilation or alteration.

I claim:

1. A stencil holder comprising a body member, a continuous metallic band encircling said member and secured thereto at an end thereof, and means for tightening said band against a surface of said member whereby a stencil may be gripped between said band and said surface.
2. A stencil holder comprising a body member, a continuous metallic band encircling said member and overlying a surface thereof, and means for pressing said band against said surface to grip a stencil or the like between said band and surface.
3. A stencil holder comprising a body member, a continuous metallic band encircling a portion of said member and fixed thereto at a point thereof, and means for drawing said band toward an outer surface of said encircled portion of said member to grip a stencil between said surface and band.
4. A stencil holder comprising an elongated body member, an elliptical metallic

band encircling a portion of said member and fixed to one end of said portion, and means cooperating with the other end of said portion for elongating said band to draw the sides thereof against the side portions of said body portion.

5. A stencil holder comprising a body member, a continuous flexible band encircling said member and overlying a surface thereof, and means cooperating between said band and member to press said band against said surface.

6. A stencil holder comprising a body member presenting a flat surface, a loop of flexible material encircling a portion of said member and having a portion thereof overlying said surface, means holding the ends of said loop fixedly positioned on said member, and means cooperating with said band and member to press said loop portion against said surface.

In testimony whereof, I have hereunto set my hand at Oakland, California, this 21st day of August, 1924.

JESSE L. MARTIN.
